UNITED STATES PATENT OFFICE.

EPHRAIM H. SWEETSER, OF SALEM, MASSACHUSETTS.

IMPROVEMENT IN BLACKING AND BRUSH HOLDERS.

Specification forming part of Letters Patent No. 124,984, dated March 26, 1872.

Specification describing a new and Improved Blacking and Brush Holder, invented by EPHRAIM H. SWEETSER, of Salem, in the county of Essex and State of Massachusetts.

My invention consists of a large flat-bottomed metal cup with a set-screw and stud, adapted for receiving and holding blacking-boxes of different sizes upon the bottom, with a long, partly-cylindrical and partly-conical case fitting on it in the place of a cover, and being open at the top to receive the daubing-brush, which I make round with a knob at the top for a handle to adapt it to fit into the top of said case for being kept in said case, and so that the top of the brush forms the cover of said case, all as hereinafter described.

Figure 1 is a section of the box and case, and side elevation of the daubing-brush. Fig. 2 is a side elevation of the case, and Fig. 3 is partly a side elevation of the cup, and partly a vertical section with a cover upon it.

Similar letters of reference indicate corresponding parts.

A is the flat-bottomed sheet-metal cup, which I make considerably larger than the largest blacking-box I wish to use, and a little higher. Within it is a stud or part of a vertical rim, B, opposite which is a set-screw, C, screwing through the side of the cup. D is the case, with a cylindrical part at the base fitting snugly in the cup like an ordinary cover, while

the conical part extends as high above as is required by the length of the brush it is to contain. It is open at the top, and the brush F, which is made round for the purpose, fits snugly in said case at the top and forms the cover. A knob, G, is made on the top of the brush for the handle. The case D may lock with the other by the angle-slot H engaging the screw by a kind of bayonet fastening. An ordinary box-cover, J, may be provided with the box A, to be used in case it is not preferred to use the case D. A hole, K, is made in the bottom of cup A to facilitate the detaching of the blacking-box L in case it sticks, but this is not essential.

This apparatus makes a neat and simple device for holding the blacking and the daubing brush, and preventing the smearing of the shelf wherever the articles are kept.

Having thus described my invention, I claim as new and desire to secure by Letters Patent.

The cup A, having rim B and set-screw C, in combination with case D, conical and open at the top, and brush F fitting therein, all as and for the purpose described.

EPHM. H. SWEETSER.
